(57) **CLAIM**

The ornamental design for a hinged outlet cover, as shown and described.

DESCRIPTION

FIG. 1 is a diagrammatic perspective view of the hinged outlet cover in the closed position in full lines with a hand and wires shown in broken lines representing environmental association matter being for illustrative purposes only and forming no part of the claimed invention.

FIG. 2 is a diagrammatic perspective view of the hinged outlet cover in the open position in full lines with wires shown in broken lines representing environmental association matter being for illustrative purposes only and forming no part of the claimed invention.

FIG. 3 is a front elevational view of the hinged outlet cover in the closed position.

FIG. 4 is a rear elevational view thereof.

FIG. 5 is a right side elevational view of the hinged outlet cover in the closed position, the left side view being a mirror image of the right side view; and,

FIG. 6 is a top plan view of the hinged outlet cover in the closed position, the bottom plan view being a mirror image of the top plan view.
